UNITED STATES PATENT OFFICE

136,708

DESIGN FOR A BOLT AND SCREW BIN

Merton D. Eastly, Oakland, Calif.

Application August 16, 1943, Serial No. 110,930

Term of patent 7 years

To all whom it may concern:

Be it known that I, Merton D. Eastly, a citizen of the United States, residing at Oakland, in the county of Alameda and State of California, have invented a new, original, and ornamental Design for a Bolt and Screw Bin, of which the following is a specification, reference being had therein to the accompanying drawing, forming part thereof, in which:

Figure 1 is an isometric perspective view of a

bolt and screw bin, showing my new design. The rear of the bin is plain and unornamented.

Figure 2 is an enlarged fragmentary sectional view, taken on line 2—2, Figure 1.

Figure 3 is a view in side elevation of one of the partitions.

What I claim is:

The ornamental design for a bolt and screw bin, as shown and described.

MERTON D. EASTLY.
